UNITED STATES PATENT OFFICE.

HENRY H. TAYLOR AND MYRON B. HAMMOND, OF BRIDGEPORT,
CONNECTICUT.

DESIGN FOR A GARMENT-SUPPORTING HOOK.

SPECIFICATION forming part of Design No. 32,383, dated March 27, 1900.

Application filed February 26, 1900. Serial No. 6,642. Term of patent 14 years.

To all whom it may concern:

Be it known that we, HENRY H. TAYLOR and MYRON B. HAMMOND, citizens of the United States, residing at Bridgeport, in the county of Fairfield and State of Connecticut, have invented and produced a new and original Design for Garment-Supporting Hooks; and we do hereby declare the following to be a full, clear, and exact description of the invention, such as will enable others skilled in the art to which it appertains to make and use the same.

Referring to the accompanying drawings, which form a part of this application, Figure 1 is a plan of our newly-designed garment-supporting hook, and Fig. 2 a side elevation of the same.

Similar numbers of reference denote like parts in both figures of the drawings.

As shown in the drawings, the leading or material features of our design consist of a

generally triangular-shaped plate 1, which terminates at the upper end in a contracted neck portion 2, and an anchor-shaped cross-bar 3, which extends from said neck portion, the latter being offset from the plate 1, so ²⁵ that when viewed in side elevation said plate and cross-bar appear in different but parallel planes and are joined by the neck.

Having thus described our invention, what we desire to secure by Letters Patent is— ³⁰

The design for a garment-supporting hook as herein shown and described.

In testimony whereof we affix our signatures in presence of two witnesses.

HENRY H. TAYLOR.
MYRON B. HAMMOND.
